UNITED STATES PATENT OFFICE.

NOBLE ANDREW FISHER, OF SACRAMENTO, CALIFORNIA.

CLUTCH FOR CABLE RAILWAYS.

SPECIFICATION forming part of Letters Patent No. 310,397, dated January 6, 1885.

Application filed August 9, 1884. (No model.)

To all whom it may concern:

Be it known that I, NOBLE A. FISHER, a citizen of the United States, residing at Sacramento, in the county of Sacramento and 5 State of California, have invented certain new and useful Improvements in Clutches for Cable Railways, of which the following is a specification, reference being had therein to the accompanying drawings.

10 This invention has relation to improvements in clutches for cable railways; and it consists in the construction and novel arrangement of devices, as will be hereinafter more fully set forth, and particularly pointed out in the 15 claims appended.

The object of my invention is to provide a cheap and simple clutching device for cable railways, by which the rope may be prevented from passing too far into the jaws and catching or binding therein. This object I accomplish by the means shown and illustrated in the accompanying drawings, in which—

Figure 1 is a representation of a perspective of my improved clutch, and Fig. 2 is a 25 similar view showing the same constructed in a modified form.

Referring by letter to the said drawings, A indicates the suspension-plate, which is provided longitudinally with the central vertical 30 slot, *a*, in which is arranged the grip-operating rod *B*. This rod is provided with slide-blocks *b*, which are designed to guide the said rod in its up and down movements through the suspension-plate, and the said rod is also 35 connected at its lower end to a transverse link or bar, *C*, which is also provided with guide-plates *d*, and is pivotally connected at its opposite ends with arms *D*, which are also hinged at their opposite ends to the lateral arms 40 *I* of the hinged clutch-jaws.

I sometimes find it preferable to construct the device as shown in Fig. 1, in which case I hinge two jaws, *E*, to the lower projecting branches, *F*, of the suspension-plate by means 45 of a transverse bolt, *G*, the suspension-plate having four of the branches, and the arms *I* of the clutches turned outwardly in opposite directions. The outer or end branches, *F*, of the suspension-plate are forked, as shown at *e*, and

the arms thereof are perforated transversely 50 for the reception of the journals of horizontal transverse friction-rollers *H*, which are designed to prevent the cable from passing beyond the proper point in the clutch or clamping-jaws.

In the construction shown in Fig. 2 but one hinged jaw is employed, the other being fixed, or a continuation of the suspension-plate, and the hinged jaw is forked or provided with suitable bearings above the cable-groove in 60 the respective jaws of the clutch, for the reception of the transverse horizontal friction-rollers *H*. The hinged clamping-jaws are respectively provided on their inner longitudinal sides with concave or other suitable grooves, 65 *h*, for the passage of the cable, and these grooves are provided at suitable intervals with friction-rollers *g*, having vertical bearings and arranged relatively at right angles to the said rollers *H*. Thus it will be seen that it does 70 not deviate from the spirit of my invention to construct a clutching device under both forms illustrated, and while I prefer to use such clutches in connection with the patented devices issued to me December 11, 1883; it will 75 be readily perceived that they may be used on roads of various constructions, and the jaws operated by any suitable mechanism.

Having thus described my invention, what I claim as new, and desire to secure by Letters 80 Patent, is—

1. In a cable-clutch, as described, the combination, with the jaws, as *E E*, having semi-grooves *h*, of friction-rollers, as *g*, journaled in the jaws and projecting into the groove, as 85 and for the purposes set forth.

2. The cable-clutch described, having the friction-rollers *g*, journaled in the jaws and operating in the groove, and having also the transverse rollers *H*, journaled in fixed bearings and directly above the groove, all combined and adapted to serve as set forth.

In testimony whereof I affix my signature in presence of two witnesses.

NOBLE ANDREW FISHER.

Witnesses:

ROBT. T. DEVLIN,
R. M. CLARKEN.
